ADVERTISING DEVICE

Filed Oct. 24, 1925

UNITED STATES PATENT OFFICE.

JOHN W. PAXSON, OF PHILADELPHIA, PENNSYLVANIA, ASSIGNOR, BY MESNE ASSIGNMENTS, TO DAVID W. PAXSON, OF PHILADELPHIA, PENNSYLVANIA.

ADVERTISING DEVICE.

Application filed October 24, 1925. Serial No. 64,594.

The object of the invention is to provide improvements in advertising media, and particularly for use after dark in the evening upon bodies of water such as rivers, large 5 lakes, bays and the ocean along the more densely populated shore line.

Another object is to provide an advertising device for this purpose comprising a barge or the like upon which large electrically illuminated figures of any desired sort are arranged to form initials, words, or in fact any symbol by which an article is widely known, such figures facing the shore whence they are easily legible to the throngs of 10 persons gathered together, as for instance at a resort, an exposition, or other water-side mecca.

A further object is to provide a barge or other suitable type of floating element 15 with a frame or lattice sufficiently stout and rigid to support, and to which are secured the letters or other figures above referred to, and when desirable there being other figures secured to and directed from the opposite side of said frame, so that either a 20 similar or different sign may be brought into the visibility of those upon the shore, piers, or boats, when the said floating element turns about and faces in the opposite direction.

Still another object is to provide suitable 25 means within the barge or other form of floating device, whereby the engine employed to propel the said floating device drives an electric dynamo or generator, which illuminates the figures of the signs, either directly 30 or through the medium of suitable storage batteries.

And a still further object is to provide 35 for a sign, or series of advertising figures, too extensive for a single floating member, carried upon a series of floats, scows, or the like, fastened together by cables and together drawn by any suitable form of power unit such as a launch, dory, or the like, the electricity for the signs being generated continuously by means within the draft unit, or supplied from batteries upon each float 40 which may have been charged during the hours of light, while the illumination of the signs is unnecessary.

With these and other objects in mind, the invention comprises further details of construction and operation fully brought out in the following description, when read in conjunction with the accompanying drawings,

in which Fig. 1 is a perspective view or artist's conception of a barge and superimposed electrically illuminated sign comprising one embodiment of the invention offshore at a pleasure resort; Fig. 2 is a side elevation of the barge and sign per se; Fig. 3 is an end elevation of the same as shown in Fig. 2; Fig. 4 is a plan view of a draft boat in order to show schematically a suitable means for generating the current for illuminating the sign; Fig. 5 is a side elevation of a series of floats, scows, or the like drawn by a suitable boat; and each of the floats carrying a sign, which taken as a whole cooperate to form a larger sign than a single boat could well carry; and Fig. 6 is a view similar to Fig. 3 but showing the oppositely directed signs extending vertically from the transverse center of the boat and maintained in fixed position by suitable stays.

Referring to Figs. 1 to 3 of the drawings, there is shown a barge 1, or any other suitable form of floating member, of such size as to safely support letters, numerals, or other desirable figures 2, said figures being of such height that, when illuminated in the manner of signs carried by fixed supports upon terra firma, and moved upon the surface of a body of water at such a distance from the shore as may be dictated by the draft of the said member, the outward extension of piers, etc., they are clearly and easily discernible with the naked eye of the average person who may be upon the shore or piers, bathing or boating nearby.

For many years advertising has been increasing rapidly and the sums spent in this connection annually have reached fabulous proportions, and still the manufacturers of widely used products continue to seek new and untried ways of calling the attention of the vast consuming public to their wares. With the perfection of the electric lamp, the illuminated sign has taken on an infinite variety of forms, fixed, changing, moving, etc., but so far as is known advantage has not heretofore been taken of the relatively black and uncluttered background offered by the water and sky off-shore, at such places as Atlantic City, N. J., where gala crowds congregate all of the year in ever increasing throngs upon the piers, the boardwalk, and in the hotels.

Here, for instance, a barge of sufficient

size can be slowly drawn up and down the shore front, out beyond the reach of the piers, and with letters or other figures of fifteen feet or more in height properly illuminated, it would form a most conspicuous, attractive and compelling display, against the dark black background of the sky and sea, as only the eerisome figures and their dancing reflections would be visible in the waves, exactly as though they floated unaided upon the surface of the water.

It is to be understood that in referring to a barge, no limitations is placed upon the character of the floating member, and the illuminated figures may obviously be of any height that may be dictated by local conditions or advertising requirements. Referring to Figs. 2 and 3, one manner of supporting the said figures upon the barge is illustrated as comprising lattices 3 of any approved form and construction, preferably assembled transversely in an A shape, while the figures, secured to these downwardly diverging frames, face in opposite directions, those upon one side being illuminated while the floating support moves in one direction, and when the latter reverses and moves in the opposite direction, those figures facing in the opposite direction being illuminated and the first set being extinguished.

The illumination of the lights of the figures may be accomplished in any desired manner, as for instance that illustrated in Fig. 4, wherein the outline 4 represents any type of boat that may be employed, its propeller 5 being driven by an engine 6, which also actuates the dynamo or generator 7, whence electric current is conveyed either directly to the lights, or to a storage battery 8 during the daylight hours and thence to the lights at night.

In Fig. 5 there is shown a series of floats, scows, or the like 9 connected together by cables 10, and drawn by a power boat 11, to which the foremost flat-boat is connected by a cable 12, it being understood that, if the electric current for the illuminated figures is not taken from storage batteries within the flat-boats, it may be transmitted by suitable conductors from a generator in the draft boat 11.

Referring to Fig. 6, instead of the oppositely directed signs 2 being supported by an A frame and slanting with respect to the

deck of the boat 1, they are positioned in the transverse center of the boat, extending longitudinally thereof and in upright parallel relation, being maintained in this position by means of suitable wire, rods, or the like, 14. Otherwise, the invention as embodied in this arrangement is similar to the constructions and operation hereinbefore described.

Having thus described my invention, what I claim and desire to protect by Letters Patent of the United States is:—

1. In an advertising device, a moving body to float upon the surface of a body of water, indicia-indicating figures, a frame upstanding from the top surface of the floating body and consisting of opposed sections, each section consisting of a marginal part with braces arranged within the marginal part intersectingly and in diamond formation to reinforce the marginal part and carry said indicia-indicating figures, said sections being inclined toward each other at the top of the frame, whereby the sections may be in close proximity with each other at the top in a direction substantially immediately above and coincident to the longitudinal center of the floating body to insure its equilibrium, and diagonal intersecting and horizontal braces to materially reinforce the sections relative to each other and additionally reinforce said first named braces.

2. In an advertising device, the combination with a body to float upon the surface of a body of water, of a frame relatively fixed on the deck of said floating body and comprising two opposed sections inclined from opposite sides of the deck toward each other and arranged in close proximity at their top portions substantially directly over and incident to the longitudinal center of the deck, each section comprising a marginal frame having reinforcing braces within it, indicia-indicating figures supported on the reinforcing braces, means adapted for illuminating the figures on one section when the floating body moves in one direction and extinguishing them and illuminating the figures on the other section when the floating body moves in the opposite direction.

In testimony whereof I have affixed my signature.

JOHN W. PAXSON.
